Patented Mar. 25, 1969

213,636

PORABLE LANTERN

William E. Burch, Post Office Drawer BU,
College Station, Tex. 77840

Filed Apr. 25, 1968, Ser. No. 11,628

Term of patent 14 years

Int. Cl. D26—04

U.S. Cl. D48—24

FIG. 1 is a perspective view taken from above the portable lantern embodying my new design.

FIG. 2 is a perspective view thereof taken from below.

FIG. 3 is a perspective view of a second embodiment of the portable lantern taken from above.

FIG. 4 is a perspective view thereof taken from below.

FIG. 5 is a perspective view of a third embodiment taken from above.

FIG. 6 is a perspective view thereof taken from below.

FIG. 7 is a perspective view of a fourth embodiment taken from above.

FIG. 8 is a perspective view thereof taken from below.

The rear of the portable lantern is flat and unornamented.

I claim:

The ornamental design for a portable lantern, substantially as shown and described.
